JACOB L. RUNK AND BENJAMIN H. THARP, OF NASHVILLE, ILLINOIS.

Letters Patent No. 101,514, dated April 5, 1870.

IMPROVEMENT IN FANNING-MILLS.

The Schedule referred to in these Letters Patent and making part of the same.

To all whom it may concern:

Be it known that we, JACOB L. RUNK and BENJAMIN H. THARP, of Nashville, in the county of Washington and State of Illinois, have invented a new and useful Improvement in Fanning-Mills; and we do hereby declare that the following is a full, clear, and exact description thereof, which will enable others skilled in the art to make and use the same, reference being had to the accompanying drawings forming part of this specification.

This invention relates to improvements in fanning-mills, and consists in the construction and arrangement of parts, as hereinafter specified.

The figure represents a longitudinal sectional elevation of our improved fanning-mill.

A represents the inclined sides of the hopper, between the lower edge of which is the throat B.

C is the adjusting-slide or gate for regulating the opening of the throat. It is arranged on the top of the upper sieve-shoe, and provided with slide-bars D, in one of which adjusting-screw E is arranged for moving it either way. The said screw is provided with a hand-crank, F, for turning it. This arrangement of the gate on the shoe facilitates the delivery of the grain, in consequence of the motion imparted to it by the shoe.

G is the agitating-rod, bent at the ends to form vertical legs, whereby it is connected to the slide C, so as to be supported above the throat in the hopper for agitating the grain, straw, and chaff by the motion it derives from the movement of the slide C, which works back and forth by the movement of the sieve-shoe, which is effected by the rock-shaft H, arm I, and connecting-rod K.

The arrangement for grading the grain consists of the two long final sieves L M, and the tilting valve N.

The sieve L is made large in the meshes, to retain only the largest grains, which are delivered out of the machine at O, while the grains dropped through the meshes fall on the sieve M, made shorter than L to deliver through P to the space Q below, or, when the valve N is turned into the position represented in dotted lines, the grain will also be delivered outside the case, and mix with that from the sieve L.

R R are bolts passing through the sides of the case, and secured by screw-nuts on their inner ends.

s s are notched metal plates, screwed to the under side of the sieve M, and forming the bearing-surfaces of said sieve on bolts R. Thus the sieve will be shaken vertically as it is reciprocated.

Having thus described our invention,

We claim as new and desire to secure by Letters Patent—

1. The rod G, slide C, and bar D, in combination with the shoe, so as to be simultaneously operated, as set forth.

2. The arrangement of the notched plates s on the sieve M, and the screw-bolts R, adjustable in slots in the case, as set forth and shown.

3. The arrangement of the valve N in connection with the long sieve L and short sieve M, so as to deliver both the coarse and fine grain outside the case, or one or both of them beneath the mill, as shown and described.
